PENCIL BOX

George Reiner, New York, N.Y., assignor to Venus Pen &
Pencil Corporation, New York, N.Y., a corporation of
New York

Filed Feb. 5, 1964, Ser. No. 78,623

Term of patent 14 years

(Cl. D58—12)

FIG. 1 is a front elevational view of a pencil box, showing my new design;

FIG. 2 is a side elevational view thereof, the opposite side being substantially the same;

FIG. 3 is a top plan view thereof;

FIG. 4 is a bottom plan view thereof;

FIG. 5 is a front perspective view thereof in open condition;

FIG. 6 is a rear perspective view of FIG. 5;

FIG. 7 is a front perspective view in open condition with the upper portion in a different position; and

FIG. 8 is a sectional view taken on line 8—8 of FIG. 1.

I claim:

The ornamental design for a pencil box, as shown and described.
